tion of Delaware

Application January 28, 1935, Serial No. 3,767

6 Claims. (Cl. 46—87)

This invention relates to inflatable hollow rubber articles such as toy balloons and to methods for making such articles, and has for its principal objects the provision of a hollow rubber article 5 which although formed in a generally rectilinear configuration will upon inflation assume a toric configuration or generally arcuate shape, and to provide economical and efficient methods for making such articles.

These and other objects of the invention are achieved by forming the article, which usually will be of relatively long slender configuration, to provide in a portion of the article a zone differing substantially in longitudinal extensibility from 10 the rest of the article so that upon inflation portions of the article will elongate more than others and cause the article to assume a desired longitudinal curvature or toric shape. In the case of a tubular article, this end may be achieved by 15 providing longitudinal zones of different extensibilities. Thus, where the zone of greater or lesser extensibility extends the length of the tubular body, the article may assume the form of a closed torus or annulus upon inflation. Similarly, where 20 the zones of greater or lesser extensibility are disposed at different elemental positions along the tubular body, the article may assume the form of tores of reverse curvature. In fact, curvilinear articles of many configurations may be produced 25 by a suitable disposition of the zones of greater and lesser extensibility.

Articles embodying the present invention are illustrated in the accompanying drawings of which

Fig. 1 is an elevation of a rubber article embodying the present invention in a preferred form in which the article is provided with a longitudinal zone of greater extensibility than the rest of the article, the article being shown in an uninflated condition;

Fig. 2 is an elevation of the article of Fig. 1 in an inflated condition and showing a toric configuration assumed by the article;

Fig. 3 is an elevation of a form suitable for use 45 in making the article of Figs. 1 and 2;

Fig. 4 is a vertical section taken on line 4—4 of Fig. 3;

Fig. 5 is an elevation of another hollow rubber article, in the uninflated condition, which embodies a modification of the present invention in which there is provided in the article a longitudinal zone or zones of restricted or lesser extensibility than the rest of the article;

Fig. 6 is an elevation of the article of Fig. 5 in an inflated condition illustrating a reversed toric configuration assumed by the article;

Fig. 7 is an elevation of a form which may be used in making the article of Figs. 5 and 6; and

Fig. 8 is a vertical section taken on line 8—8 of Fig. 7.

A hollow rubber article embodying the present invention in a preferred form comprises a tubular body 10 of extensible rubber composition of suitable, preferably uniform, wall thickness, the body preferably being formed in a generally rectilinear, 5 relatively long and slender configuration. The body is entirely closed and fluid tight except for an inflation opening 11 which conveniently may be at one end of the body 10. To provide a longitudinal zone of greater extensibility than the inherent extensibility of the rubber body itself, a series of protuberances 12 are provided along one side of the body 10, the protuberances preferably being arranged in substantially regularly spaced 10 positions in longitudinal alignment in such manner as to provide in effect a sinuously formed longitudinal zone extending only part way around the circumference of the body of the article, and continuing for a sufficient portion of the length of the body to produce, upon inflation, a desired 15 degree of longitudinal curvature.

When the article of Fig. 1 is inflated, both the circumferential and the longitudinal dimensions of the body 10 will be increased to an extent depending upon the degree of the inflation, but 20 the longitudinal extension of the body will not be uniform throughout the article, for the sinuously formed zone will extend in an accordion-like manner to a considerable degree without stretching the rubber body any, whereas extension 25 in the rest of the body results only from actual stretching of the rubber itself. As a consequence of such uneven longitudinal extension, the article upon inflation assumes a longitudinally curved or toric configuration, and, if the 30 sinuously formed zone extends for substantially 35 the entire length of the article, and the article is inflated sufficiently, it may be caused to assume a closed toric configuration to produce an annulus as illustrated in Fig. 2.

To make the article of Figs. 1 and 2 according to a preferred method, a form 15 of any suitable material and having the desired shape of the uninflated body 10 is provided. For example, the form 15 may be made of metal, glass, bakelite, 45 porcelain, or similar material, and may be either porous or non-porous as desired. The form 15 preferably comprises a relatively long slender and substantially circular body-forming member 16 provided with a series of radially eccentric circumferential ridges 17 extending part way around the form and being arranged in longitudinal alignment. Having provided the form 15, it preferably is immersed in a suitably compounded liquid dispersion of rubber and a film or coating of rubber is deposited upon the form by any of the well-known processes, and the deposited rubber is dried, vulcanized and stripped from the form to provide the uninflated rectilinear article 50 of Fig. 1. This rectilinear article then is inflated 55 55 60 65 70 75 80 85 90 95 100 105 110 115 120 125 130 135 140 145 150 155 160 165 170 175 180 185 190 195 200 205 210 215 220 225 230 235 240 245 250 255 to produce in the manner described, a toric article such as that of Fig. 2.

A hollow rubber article embodying a modified form of the invention in which the article is provided with a longitudinal zone of restricted or lesser extensibility than the rest of the article is illustrated in Figs. 5 and 6 and comprises a tubular body 20 of generally rectilinear configuration formed of extensible rubber composition, preferably of substantially uniform wall-thickness. Like the body of the previously described article, the body 20 is fluid tight except for an inflation opening 21 which may be at one end thereof or otherwise conveniently located. The desired zone of restricted extensibility is obtained by providing, preferably upon the interior of the body 20, one or more integrally formed ribs 22, extending longitudinally of the body for a substantial distance. If several ribs are provided, they preferably are disposed in parallel relationship in a relatively narrow circumferential zone of the body to provide the desired zone of restricted extensibility. The rib or ribs may extend for substantially the entire length of the body or for shorter distances depending upon the particular type of curvature or toric configuration desired. Also, more than one zone of different extensibility may be provided to produce more complicated curved configurations. For example, the article of Fig. 5 is provided with two zones 23 and 24 of restricted extensibility spaced circumferentially 180° apart, each zone extending approximately half the length of the body. When such an article is inflated, half the article will curve in one direction, and the other half will curve in the opposite direction producing an article of reversed toric configuration or S shape as illustrated in Fig. 6.

The hollow rubber article of Figs. 5 and 6 may be made in a manner generally similar to that previously described for making the article of Figs. 1 and 2, the principal differences being in the form required. In the present example, a suitable form illustrated in Figs. 7 and 8 comprises a rectilinear and substantially circular body-forming member 25 of relatively long and slender configuration, made of any suitable material. The form is provided with two groups 26 and 27 of grooves 28 disposed in parallel relationship and extending longitudinally of the form, the two groups being disposed at different elemental positions along the form and spaced circumferentially 180° apart. When such a form is immersed in a liquid dispersion of rubber and rubber is deposited upon the form, the grooves 28 are filled with rubber to produce ribs integral with the main coating of rubber constituting the body of the article. After the rubber is deposited upon the form, it is dried, vulcanized and stripped from the form in the usual manner, and the article is inflated, whereupon it assumes the desired toric configuration.

Inflated articles of many shapes and varied toric configurations may be produced by suitably disposing the zones of greater or lesser extensibility upon the body of the article, and it is understood that the two configurations shown in the drawings have been chosen merely for the purpose of illustrating the invention and without intent to limit the discovery to any particular toric configuration.

While the present invention is especially useful in the manufacture of toy balloons of a wide variety of designs and shapes, the principles herein described are capable of numerous other appli-

cations and may be utilized for example in making invalid cushions, in which case the inflated toric cushion may be used with or without an enclosing covering or casing of fabric or other material, bladders for inflatable circular boats, and similar articles.

Numerous variations and modifications in details of the invention as hereinabove described may be made without departing from the spirit and scope of the invention as defined by the appended claims.

I claim:

1. An inflatable hollow rubber article capable of assuming a toric configuration when inflated comprising a generally rectilinear tubular body of extensible rubber composition having a longitudinal zone of materially greater extensibility when subjected to inflation than another longitudinal zone of the body, whereby the tubular body upon inflation will assume a toric configuration.

2. An inflatable hollow rubber article capable of assuming a toric configuration when inflated comprising a generally rectilinear tubular body of extensible rubber composition having a substantially uniform wall thickness throughout, the body wall in a determinate region being formed in non-planar fashion to provide a relatively narrow longitudinal zone of materially greater extensibility when subjected to inflation than adjacent portions of the body, whereby the tubular body upon inflation will assume a toric configuration.

3. An inflatable hollow rubber article capable of assuming a toric configuration when inflated comprising a generally rectilinear tubular body of extensible rubber composition having a substantially uniform wall thickness throughout, the body wall being sinuously formed in a determinate region to provide a longitudinal zone of materially greater extensibility when subjected to inflation than adjacent portions of the body, whereby the tubular body upon inflation will assume a toric configuration.

4. An inflatable hollow rubber article capable of assuming a toric configuration when inflated comprising a generally rectilinear tubular body of extensible rubber composition having a substantially uniform wall thickness throughout, and an integral localized extensibility-restricting element extending longitudinally of the body for a substantial distance to provide a relatively narrow longitudinal zone of materially lesser extensibility when subjected to inflation than adjacent portions of the body, whereby the tubular body upon inflation will assume a toric configuration.

5. An inflatable hollow rubber article capable of assuming a toric configuration when inflated comprising a generally rectilinear tubular body of extensible rubber composition having a longitudinal integral rib serving to restrict extension of the article in a longitudinal zone about the rib upon inflation whereby the tubular body will assume a toric configuration.

6. An inflatable hollow rubber article capable of assuming a toric configuration when inflated comprising a generally rectilinear tubular body of extensible rubber composition having a plurality of integrally formed longitudinal ribs disposed in parallel relationship in a relatively narrow longitudinal zone of the body and serving to restrict extension of the article in said zone upon inflation whereby the tubular body will assume a toric configuration.
